MORITZ L. MUELLER, OF SEATTLE, WASHINGTON, ASSIGNOR TO NORTHWEST BLOWER KILN COMPANY, OF PORTLAND, OREGON, A CORPORATION OF WASHINGTON

METHOD OF AND MEANS FOR DRYING LUMBER

Application filed August 22, 1928. Serial No. 301,324.

This invention relates to a method of and means for drying lumber and more particularly to the drying of flat piled lumber. The drying of lumber when piled flat presents a difficult problem. It is usually piled in units (loads), the edges of which form an even line. Spacers are used between the several courses of lumber so that below the edge of each course there is a space for the entrance of air which conducts heat to the material and conducts moisture away from it.

One of the important objects of the present invention is to so direct, adjust and control the flow of the air as to cause all of the various courses of the material to dry at an even rate. This is desirable in order to prevent part of the lumber lagging behind in its drying after the balance is finished. It is additionally desirable because the rate of air flow controls the quality of the dried stock.

Broadly stated the invention resides in directing the drying air at such an angle with respect to the vertical side of the pile of lumber that the overhanging edges of the several courses catch the air and direct it by a deflecting action through the various channels between the courses of the lumber.

The invention further resides in so directing and controlling the air currents that substantially all parts of the pile will receive the same treatment.

The invention further contemplates the provision of means for reversing the direction of current flow, in combination with the angular discharge of the air toward the pile of lumber, as above set forth. By virtue of this reversal of current flow and the blowing of the air into the material first from one direction and then from the other I avoid the necessity for a high degree of refinement and accuracy of the air control and am able to secure all necessary practical results with much less expense than would otherwise be the case.

A further object of the invention is to so locate and adjust and design the deflectors, used to secure the above described results, that air surrounding the moving air stream will be induced to enter the stream, thus giving a larger total air flow than that set up by the air circulating mediums, hereinafter de-

scribed. This saves power, inasmuch as standard equipment of small capacity can be made to produce abnormally large air movements in a closed circuit air stream.

In the accompanying drawings, which are merely illustrative of the principles involved in the present invention;

Fig. 1 is a diagrammatic transverse sectional view through a lumber drying kiln, the air flow through the lumber being from right to left;

Fig. 2 is a view like Fig. 1 but with the deflectors adjusted to set up a circulation of air from left to right, through the lumber;

Fig. 3 is a transverse vertical sectional view through a lumber drying kiln illustrating a modified arrangement of deflectors;

Fig. 4 is a view similar to Fig. 3 modified to illustrate a circulating fan;

Fig. 5 is an enlarged sectional view through a portion of the edge of one of the lumber piles, and

Fig. 6 is a diagrammatic view, hereinafter described.

Referring now to the drawings and more particularly to Figs. 1 and 2, 5 designates a lumber drying kiln of a conventional type provided with track rails 6 upon which lumber trucks 7 may be run into the kiln. A pile of lumber to be dried is indicated at 8. The courses of the lumber, indicated at 9, are spaced from each other by transverse spacing strips 10, the result being to leave the pile of lumber honey-combed with a multiplicity of transverse channels 11.

It is common practice in the lumber drying art to locate a longitudinally extending pressure duct 12 and longitudinally extending suction ducts 13 in the lower portion of lumber drying kilns and I have utilized such an arrangement in the present invention but have combined novel deflectors therewith in such a way as to bring about a new and highly advantageous control of the air flow.

In Fig. 1 a curved deflector 14 is pivoted at 15 so that it may be thrown from the position illustrated in Fig. 1 to the position illustrated in Fig. 2. With the deflector 14 set in the position illustrated in Fig. 1 and with the dampers or closures 16 of the left hand suc-

tion duct open and the dampers of the right hand suction duct closed as indicated at 17, the flow of air will be from right to left through the pile of lumber as indicated by the arrows. That is to say pressure air from duct 12 being discharged upwardly will be caught by the deflector 14 and deflected toward the right hand side of the kiln. A series of curved deflectors 18, 18^a, 18^b catch the air and direct it upwardly and inwardly; in such manner that it strikes the vertical side of the pile of lumber at varying points in the height of the pile. In other words the air is distributed substantially uniformly over the entire side 15 of the pile of lumber throughout the height of said pile.

The flow of air to the right from the deflector 14 creates an injector action at the constricted openings Z at the lower and upper edges of said deflector, thus drawing into the air stream air from the lower portion of the kiln that would not otherwise be drawn into the air stream. The air that is discharged past the deflectors 18, 18^a, 18^b at an acute angle toward the side of the lumber pile is caught by the overhanging edges 19 (see Fig. 5) of the several courses of lumber and directed through the channels 11 as indicated by the arrows. At the lower left hand side of the kiln a part of this air is drawn into the suction duct 13, returning to the air stream through the pressure duct 12 in a manner quite common in lumber drying kilns.

The structure illustrated in Fig. 2 is like that illustrated in Fig. 1 except that the deflector 14 has been tipped upon its hinge or pivot 15 in such manner that air discharged out of the top of the pressure duct 12 is caused to travel toward the left. In this case the damper 17 of the right hand suction duct is open and the damper 16 of the left hand suction duct is closed. The flow of the air will then be as indicated by the arrows past deflectors 18^c, 18^d and 18^e. The same injector action takes place at the edges of the deflector 14.

In Fig. 3 the arrangement of parts is the same except that deflectors 18^c, 18^e, 18^h and 18ⁱ, 18^k are substituted for the corresponding deflectors of Figs. 1 and 2. These latter deflectors instead of being in two groups in substantially the same horizontal plane are disposed at varying points in the height of the kiln.

In Fig. 4 a fan 20 is used as the circulating medium in lieu of the pressure and suction duct and in this case reversal of current flow is secured by reversing the direction of rotation of the fan. In this form of the invention groups of diffusion deflectors 18^l, 18^m are used in conjunction with the vertically spaced diffusion deflectors 18ⁿ, 18°, it being noted that the lowermost of these last named deflectors are spaced further from the side walls of the kiln than the intermediate

ones of said deflectors and that said intermediate deflectors are spaced further from the side walls of the kiln than the uppermost of said deflectors. Consequently different portions of the vertically moving air stream are caught and deflected at an angle to and beneath the overhanging edges of the several courses of lumber, the result being to supply a substantially uniform quantity of air to all portions of the pile.

As far as I am aware I am the first to direct air at an angle against the edges of flat piled material for the purpose described. It has long been the practice to pile lumber upon trucks in this fashion and to deliver air from below or above the space between the lumber and the kiln wall in such manner that the air travels in a vertical direction. The problem has been to cause this vertical air current to be diffused evenly into horizontal air spaces exceeding in total area the throat (entrance space) of the distributing chamber.

Heretofore baffles have been used to close this chamber so that by stopping the natural flow of the air a back pressure was created. This back pressure following the law of static action causes the bulk of the air to enter horizontal spaces nearest the obstructing baffle. Further, this static pressure dwindles rapidly in most cases away from such point with the result that there is a difference in the volume of air passing between the upper and lower parts of the loads.

The principles of deflection and diffusion, however, may be used to overcome this result. Air flow, like light, follows certain laws of deflection and diffusion. Air striking an obstruction at an acute angle leaves the obstruction at an equivalent angle. A stream of air diffuses in a cone shaped stream, the side angles of which in relation to the average direction, are acute in proportion to the velocity, momentum and other set characteristics of the air.

I propose by the use of various deflectors to control the air flow from any source in such manner as to produce the proper angle in relation to the edge of the load, required to distribute the air evenly into such load, it being apparent that a constant angle will produce even distribution.

The reversing deflector 14 may be set to other than its extreme position. This deflector not only reverses the air flow but it also serves, by a proper adjustment, to control the angle at which the air stream strikes the kiln wall or the other deflectors. A sharper arc or a stronger pitch of this deflector may raise or lower the air stream. The secondary deflectors located at the juncture of the air stream with its first obstruction (the wall at the rail line), or in the vertical space between the load and the wall, or in both places, controls the angular travel of

the air through deflection and the shape of diffusion of the air stream by obstruction. The number and location of the deflectors may be varied at will, this being governed by the load, spaces, dimensions etc. in individual cases.

- Fig. 6 is a diagrammatic view of a modified form, wherein the pressure duct 12^a and the suction ducts 16^a-16^b have flat tops. The full line arrows in this figure show how the air may be deflected directly from the deflector 14^a against the side wall of the kiln and thence to the edges of the lumber at one point, while the dot and dash arrow indicate how, with the deflector set in another position, the air may be deflected first against the flat top of the suction duct, thence to the side wall of the kiln and thence against the edges of the lumber at a different point. The use of this arrangement renders it possible to dispense, in some constructions, with the side deflectors, and is of importance.

It is to be understood that the invention is not limited to the use of any particular mechanism, but that it includes within its purview whatever changes fairly come within either the terms or the spirit of the appended claims.

Having described my invention what I claim is:

1. The combination with a kiln, and means for setting up a circulation of air transversely thereof, of deflecting means at each side of the kiln comprising a group of horizontally spaced deflectors adjacent the lower portion of each side wall of the kiln, a centrally arranged pressure duct discharging air upwardly, and a pivoted deflector above the pressure duct arranged to direct the air discharged therefrom to either of said groups of deflectors.

2. The combination with a kiln, and means for setting up a circulation of air transversely thereof, of deflecting means at each side of the kiln comprising a group of horizontally spaced deflectors adjacent the lower portion of each side wall of the kiln, a centrally arranged pressure duct discharging air upwardly, and a pivoted deflector above the pressure duct arranged to direct the air discharged therefrom to either of said groups of deflectors, suction ducts at each side of the kiln and independently operable closures for the ports of each of said suction ducts.

3. The combination with a kiln and means for setting up a circulation of air transversely thereof, comprising a centrally disposed longitudinally extending pressure duct, said pressure duct discharging air upwardly from the top thereof, of deflecting means in the kiln arranged to direct the air between the side wall of the kiln and the pile of lumber, and deflecting means comprising an arcuate deflector mounted for tilting movement above the pressure duct, said arcuate deflector di-

recting the air discharged from said pressure duct to said deflecting means.

4. The combination with a kiln and means for setting up a circulation of air transversely thereof, comprising a centrally disposed longitudinally extending pressure duct, said pressure duct discharging air upwardly from the top thereof, of deflecting means in the kiln arranged to direct the air between the side wall of the kiln and the pile of lumber, and deflecting means comprising an arcuate deflector mounted for tilting movement above the pressure duct, and in such spaced relation thereto as to permit the drawing of induced air into the air stream from the suction side of said deflector.

5. The combination with a kiln, and means for setting up a circulation of air transversely thereof, of deflecting means in the kiln arranged to direct the air currents against the vertical sides of piles of lumber, flat piled in spaced courses at such angles that the edges of said courses catch and deflect the air currents through the channels between said courses, substantially throughout the entire height of said piles, the means for setting up a circulation of air in the kiln comprising a centrally arranged pressure duct and suction ducts upon opposite sides thereof, said suction ducts being located substantially beneath the space between the side wall of the kiln and the pile of lumber, and an arcuate deflector mounted for tilting movement above the pressure duct and adapted to direct the air discharged therefrom in either direction.

6. The combination with a kiln and means for setting up a circulation of air transversely thereof, of deflecting means in the kiln comprising a horizontally spaced group of deflectors at the lower end of the space between the piles of lumber in the kiln and the side walls of the kiln, the several deflectors being of such size and shape as to direct a plurality of streams of air against the sides of the piles of lumber at varying points in the height thereof, so that when said streams are discharged against the piles of lumber, flat piled in spaced courses, the exposed lower edges of said courses catch and deflect the air currents through the channels between said courses, a centrally arranged pressure duct, and a movable deflector mounted for tilting movement thereover to vary the direction of air flow toward the horizontally spaced group of deflectors.

7. The combination with a kiln and means for setting up a circulation of air transversely thereof, a plurality of sets of deflecting means in the kiln at each side of said kiln, and substantially beneath the spaces between the side walls of the kiln, and piles of lumber flat piled in spaced courses in said kiln, said deflecting means being disposed at such angles and in such positions, with respect to

each other and with respect to the piles of lumber, as to direct the air currents against the vertical sides of said lumber piles, at varying points substantially throughout the entire height thereof and at such angles that the overhanging edges of said courses of lumber catch and deflect the air currents through the channels between said courses, substantially throughout the entire height of said piles, a centrally arranged pressure duct beneath the lumber piles, and a tilttable deflector above the pressure duct serving to direct the air currents therefrom to either one or the other of said sets of deflecting means.

8. The combination with a kiln and means for setting up a circulation of air transversely thereof, a plurality of sets of deflecting means in the kiln at each side of said kiln, and substantially beneath the spaces between the side walls of the kiln, and piles of lumber flat piled in spaced courses in said kiln, said deflecting means being disposed at such angles and in such positions, with respect to each other and with respect to the piles of lumber, as to direct the air currents against the vertical sides of said lumber piles, at varying points substantially throughout the entire height thereof and at such angles that the overhanging edges of said courses of lumber catch and deflect the air currents through the channels between said courses, substantially throughout the entire height of said piles, a centrally arranged pressure duct beneath the lumber piles, and a tilttable deflector above the pressure duct serving to direct the air currents therefrom, to either one or the other of said sets of deflecting means, said deflector being mounted in such spaced relation to the pressure duct as to permit the drawing of induced air into the air stream from the suction side of said deflector.

9. The combination with a kiln and means for setting up a circulation of air transversely thereof, of deflecting means in the kiln arranged to direct the air currents against the vertical sides of piles of lumber, flat piled in spaced courses at such angles that the edges of said courses catch and deflect the air currents through the channels between said courses, substantially throughout the entire height of said piles, the means for setting up such circulation of air in the kiln comprising a centrally arranged pressure duct and a group of deflectors lying beneath the space between the pile of lumber and the side wall of the kiln, all of said deflectors being disposed in substantially the same horizontal plane, and the several deflectors being disposed in such positions and at such angles and presenting such surfaces that the air discharged by each deflector will strike the pile of lumber at a point different from that at which the air from any other of said deflectors strikes said pile, said deflectors being spaced from each other to present open chan-

nels between them, and means for directing the air from the centrally arranged pressure duct into the lower ends of the channels between the deflectors.

10. A structure as recited in claim 9, wherein the means for directing the air from the centrally arranged pressure duct to the horizontal group of deflectors comprises a deflector located above the pressure duct and shaped to turn the air toward the horizontal group of deflectors.

In testimony whereof I affix my signature.
MORITZ L. MUELLER.
